UNITED STATES PATENT OFFICE.

JOHN B. DAVIS, OF TOLEDO, OHIO, ASSIGNOR TO THE CITY MACHINE & TOOL COMPANY,
OF TOLEDO, OHIO, A CORPORATION OF OHIO.

DESIGN FOR A LIQUID DISPENSING AND REGISTERING PUMP.

46,813.

Specification for Design.

Patented Jan. 5, 1915.

Application filed September 21, 1914. Serial No. 862,816. Term of patent 7 years.

To all whom it may concern:

Be it known that I, JOHN B. DAVIS, a citizen of the United States, residing at Toledo, in the county of Lucas and State of Ohio, have invented a new, original, and ornamental Design for a Liquid Dispensing and Registering Pump, of which the following is a specification, reference being had to the accompanying drawing, forming a part thereof.

In the drawings, Figure 1 is a perspective

elevation of a pump showing my new design, and Fig. 2 is a side elevation thereof.

I claim:

The ornamental design for a liquid dispensing and registering pump, substantially as shown.

JOHN B. DAVIS.
